UNITED STATES PATENT OFFICE.

WILLIAM A. MUSHATT, OF BRAINERD, MINNESOTA.

STUMP-PULLER.

No. 822,861.

Specification of Letters Patent.

Patented June 5, 1906.

Application filed August 9, 1905. Serial No. 273,472.

To all whom it may concern:

Be it known that I, WILLIAM A. MUSHATT, a citizen of the United States, residing at Brainerd, in the county of Crow Wing, State 5 of Minnesota, have invented certain new and useful Improvements in Stump-Pullers; and I do hereby declare the following to be a full, clear, and exact description of the invention, such as will enable others skilled in the art to 10 to which it appertains to make and use the same.

This invention relates to stump-pullers.

One object of the invention is to provide an exceedingly simple, inexpensive, durable, 15 and efficient device of the character stated.

Another object of the invention resides in the provision of a stump-puller embodying such characteristics that stumps may be readily upset from the ground.

20 With these and other objects in view the present invention consists in the combination and arrangement of parts, as will be herein-after more fully described, shown in the accompanying drawings, and more particularly 25 pointed out in the appended claims, it being understood that changes in the form, proportion, size, and minor details may be made within the scope of the claims without departing from the spirit or sacrificing any of 30 the advantages of the present invention.

In the drawings, Figure 1 is a side elevation of my invention. Fig. 2 is a top plan view. Fig. 3 is a transverse section. Fig. 4 is a longitudinal section.

35 Referring now more particularly to the accompanying drawings, the reference character 1 designates a base-plate, and the reference character 2 a top plate, one end of the top plate having its sides converging toward 40 each other, as at 3 and 4, the base-plate 1 having perforations 5 therein, whereby it may be secured firmly to the ground.

45 Journaled through one end of the upper and lower plates 2 and 1, respectively, are the reduced ends 6 and 7 of the drum 8, there being a vertical rotatable shaft 9, having its reduced ends 10 and 11 journaled through the said upper and lower plates, respectively, and being in spaced relation to the drum 8, 50 the extremities of the reduced ends of the drum 8 and the shaft 9 being received by suitable bearing-boxes 12, arranged upon the exterior faces of the plates 1 and 2.

As the result of reducing the ends of the drum 8 and the rotatable shaft 9 shoulders 13

and 14, respectively, are formed. Arranged between the upper plate 2 and the shoulders 13 and 14 of the drum 8 and shaft 9 is a plate 15, having its sides at one end converging to conform to the convergency of the sides 3 60 and 4 of the plate 2, there being another plate 16 disposed between the shoulders 13 and 14 at the lower ends of the drum and shaft and the inner face of the base-plate 1. Fitted upon the upper reduced end 14 of the 65 shaft 9 is a pinion 17, designed to mesh with the gear-wheel 18, disposed upon the upper reduced end 13 of the drum 8, it being seen that the said pinion 17 and gear-wheel 18 are disposed between the plates 2 and 15, 70 thereby holding the said plates in spaced relation with respect to each other.

A pinion 19 is secured upon the lower reduced end 14 of the shaft 9 between the plates 1 and 16 for mesh with the gear-wheel 75 20, disposed upon the lower reduced end 13 of the drum between the last-mentioned plates, thereby supporting the latter in spaced relation to each other. It will be noted that the plate 16 has the sides at one end converging 80 to conform to the convergency of the sides 3 and 4 of the plate 2.

Oppositely-disposed stays 21 and 22, each having upper and lower bent ends 23 and 24, respectively, are disposed in alinement with 85 the drum 8, the upper bent ends 23 of each stay being bent over the upper face of the plate 15 and pierced by a bolt 25, which latter is also passed through the upper plate 2 and the plate 15 to hold the said plates together and also the upper end of the stays 21 and 22 with respect to the plates, the lower bent end 24 of the stays 21 and 22 being disposed against the under face of the plate 16 90 therebetween and the base-plate 1, there being a bolt 26 passed through the said plates 1 and 16 and the bent ends 24 of the stays 21 and 22 for the same purpose as is the bolt 25 associated with the upper ends of the stays. A third stay 27 has its upper end bent, as at 95 28, for engagement between the converging ends of the upper plates 2 and 15, there being a bolt 29 piercing the said plates and bent end 28 of the stay 27. The lower end of the stay 27 is bent inwardly, as at 30, between the convergent sides of one end of the plate 16 and the base-plate 1 and secured therebetween by means of a suitable bolt 31. It will be observed that the stay 27 is arranged intermediate the aforesaid stays 21 and 22 100

105 110

and in advance or rearwardly of the latter. This intermediate stay is curved outwardly, as at 32, with respect to the corresponding ends of the aforesaid plates, and the sides of 5 the stay intermediate the said ends are beveled or curved, as at 33, by bending outwardly upon the stay, such formation of the inner side of the intermediate stay resulting in a groove 34 upon its outer face.

10 The intermediate or third stay 27 is designed to receive both ends 35 and 36 of a chain or other connection 37, which is fitted over or around the tree or stump, as shown, there being a chain or other connection 38 15 secured to the drum 8 and designed for connection at its opposite end with a tree or stump. Now in order to upset or extract either one or both of the stumps or trees just alluded to it is simply necessary to connect 20 the horses or other draft (not shown) in any suitable manner to the beam 39, which is connected to the upper squared end 40 of the vertical shaft 9, and cause the draft to pass around the device, such movement of the 25 draft causing rotation of the vertical shaft 9, and by reason of the pinions 17 and 19, fixedly secured thereto, cause the gear-wheels 8 and 20, with which said pinions mesh, to compel a rotation of the drum 8, it being obvious 30 that rotation of the drum 8 will cause a tightening of the chain or other connection 38 and pull the stump with which it is connected out of the ground. Of course the strain between the puller and both stumps or

trees will have a tendency to loosen and extract both stumps or trees simultaneously. 35

What is claimed is—

1. A stump-puller comprising pairs of upper and lower plates, a drum journaled in said plates, a shaft journaled in said plates in spaced relation to the drum, stays connecting each pair of plates, a beam connected to one end of said shaft whereby the latter may be rotated, and means arranged between the shaft and the drum for rotating the latter 45 upon rotation of the former.

2. A stump-puller comprising pairs of upper and lower plates, a drum journaled for rotation through said plates, upper and lower gear-wheels fixedly mounted upon said drum 50 between the corresponding upper and lower plates, a vertical shaft journaled through said upper and lower pairs of plates, upper and lower pinions mounted upon said shaft between the corresponding pairs of plates for 55 mesh with the aforesaid gear-wheels, stays arranged between the upper and lower pairs of plates, a beam connected to one end of the said shaft whereby the latter may be rotated to cause a rotation of the drum simultaneously therewith through the instrumentality 60 of the aforesaid pinions and gear-wheels.

In testimony whereof I affix my signature in presence of two witnesses:

WILLIAM A. MUSHATT

Witnesses:

B. P. SWANSON,
RALPH LYONS.
